UNITED STATES PATENT OFFICE.

GEORGE CROSSLAND, OF AMSTERDAM, NEW YORK, ASSIGNOR TO MOHAWK CARPET MILLS, INC., OF AMSTERDAM, NEW YORK, A CORPORATION OF NEW YORK.

TUBE FRAME FOR LOOMS.

Application filed April 3, 1925. Serial No. 20,533.

This invention relates to looms for weaving tufted fabrics such as, for example, Axminster rugs, and relates more particularly to an improved form of tube frames to be used in such looms. Ordinarily an Axminster tube frame is provided with means for holding a spool of tufting yarn, from which spool yarn is supplied to the tubes mounted on the frame. The tube frame which is the subject of this invention, is designed for use with a novel type of loom in which the spools of tufting yarn are rotatably mounted on the stationary loom frame, instead of being mounted directly on the movable tube frames. A loom in conjunction with which the tube frame described herein is adapted to be used, is fully described and claimed in my co-pending application Serial No. 20,534 filed concurrently herewith.

It is an object of this invention to provide a tube frame of novel construction adapted to be used with a supply of yarn which is mounted independently of the tube frame itself.

It is a further object of this invention to provide means for clamping the yarn to prevent it from being pulled out of the tubes during movement of the tube frame toward or from the shed, said clamping means being releasable during a portion of the movement of the tube frame from the shed to permit the tube frame to move relatively to the yarn.

Other objects and advantages of my invention will be apparent from the following description, taken in conjunction with the accompanying drawings, which form a part of this specification, and in which:

Figure 1 is a front elevation of a tube frame constructed according to my invention, the sheet metal guard being shown in dot and dash lines;

Figure 2 is a cross-sectional view of the same taken on the line 2—2 of Figure 1; and

Figure 3 is a similar view taken on the line 3—3 of Figure 1.

Referring more particularly to the drawings, in which like reference characters denote like parts throughout the several views thereof, my improved tube frame comprises a body or bar 10, which is preferably a hollow bar of rectangular cross-section, upon which are mounted tubes 11. The bar 10 is provided with end brackets 12, in a recess

in the back of each of which is riveted the post of a standard ear assembly, having an ear 13 and a spring hook 14. The brackets 12 also carry between them a rotatable shaft 15 and a fixed shaft 16. Braces 17 are mounted on these two shafts and serve to hold the tubes 11 against vibration. Only one such brace 17 is shown in the drawings but it is to be understood, of course, that as many as desired may be supplied.

Yarn clamps 18 are mounted above the tubes 11 and serve to prevent the yarn from being pulled out of the tubes. This clamp is in the form of a bar extending longitudinally of the tube frame immediately above the tubes, and is made in several sections, as shown, in order that an even bearing surface on the yarn may be secured throughout the full length of the tube frame. The bars or clamps 18 are carried at each end upon arms 19 rotatably mounted upon the fixed shaft 16. Collars 20 fixedly mounted upon the shaft 16 hold one end of a spring 21, the other end of which bears upon the arm 19 in such manner as to hold the clamp 18 firmly against the yarn. The rotatable shaft 15 is provided with arms or dogs 22, fixedly secured thereto, one of which engages each arm 19. A finger or trigger 23 is also secured to each end of the rotatable shaft 15 and is adapted to be engaged by suitable mechanism on the loom to rotate the shaft 15 at proper times. Upon such movement of the shaft 15 the dogs 22 will force the arms 19 outwardly against the action of the springs 21 and thereby permit relative movement of the tube frame and yarn.

A small rod or wire 24 is placed immediately above the upper ends of the tubes 11, in order to properly guide the yarn into the tubes and prevent chafing of the yarn. A sheet metal guard 25 is secured to the end brackets 12 and prevents the yarn from coming in contact with the shafts 15 and 16 and the parts thereon. This guard is shown in dot and dash lines in Figure 1 for the sake of clarity and ease of disclosure, but is shown in Figures 2 and 3 in section. An ear 26 is struck up from each end of the sheet metal guard 25, and is provided with a hole for the attachment of a chain, the purpose of which is to operate the tensioning mechanism briefly referred to below, and fully described in my above-named co-pending application.

The manner of use of my improved tube

frame is explained at length in my co-pending application above referred to, and it is considered unnecessary to repeat this matter here. It is sufficient here to state merely that the tube frame is carried on a chain by means of the ears 13 and spring hooks 14 in a manner well known in the prior art. The yarn, however, instead of being drawn from a spool mounted directly on the tube frame, is drawn from a spool mounted on a stationary part of the loom, or on an independent frame or creel. The tube frame is seized by the usual clutches or transfer arms, removed from the carrying chain, and presented at the fell of the fabric. The clamps 18 prevent the yarn from being pulled out of the tubes, and serve to hold the yarn so that some is drawn from the supply beam while the tube frame is moving downward. The tuft is then made and bound in place in the usual manner, and before shearing takes place, the triggers 23 are operated by mechanism on the loom to release the clamps 18 for a portion of the upward movement of the tube frame sufficient to leave yarn ends of the proper length projecting beyond the tubes. The yarn is then cut by the knives on the loom, and the tube frame replaced on the carrying chain by the transfer arms. Suitable tensioning mechanism on the loom is employed to take up the slack in the yarn caused by the upward movement of the tube frame after the clamps 18 re-engage the yarn. The carrying chain is then moved, and the operation repeated with the next tube frame in the sequence.

Experience has shown that a single clamp 18, extending across the entire tube frame, is impractical where a wide tube frame is used, because it will clamp part of the yarn and leave other parts unclamped. The reason for this is probably that the tube frames do not present a perfectly uniform plane surface against which clamping may be effected. A plurality of clamps 18 is therefore provided, each of which acts independently in clamping the yarn, but which are all actuated substantially simultaneously as a unit in releasing the yarn, which action is accomplished by means of the triggers 23 and dogs 22, all fast to rotatable shaft 15.

Many alterations or modifications might be made in the structure above disclosed by one skilled in the art without affecting the essential features of my invention, and such changes are within the intent of the appended claims.

Having thus described the invention, what is claimed as new and desired to be secured by Letters Patent is:

1. In a tube frame adapted to be supplied with yarn from a source mounted independently thereof, a bar having tubes secured thereto, a plurality of yarn ends extending

thru said tubes, clamping means turning about a fixed pivot on said tube frame for preventing movement of the yarn relative thereto, and means for normally holding said clamping means in engagement with the 70 yarn.

2. In a tube frame adapted to be supplied with yarn from a source mounted independently thereof, a bar having tubes secured thereto, a plurality of yarn ends extending 75 thru said tubes, yarn clamping means turning about a fixed pivot on said tube frame, means for holding said clamping means in engagement with the yarn, whereby movement of the yarn relative to the tube frame is prevented, and means for disengaging said clamping means.

3. In a tube frame adapted to be supplied with yarn from a source mounted independently thereof, a bar having tubes secured 85 thereto, a plurality of yarn ends extending thru said tubes, yarn clamping means turning about a fixed pivot on said tube frame, means for holding said clamping means in engagement with the yarn, whereby movement of the yarn relative to the tube frame is prevented, and means for disengaging said clamping means, said disengaging means being constructed and arranged to be operated by mechanism on the loom. 90

4. In a tube frame, in combination, a bar having tubes secured thereto, a spring-pressed yarn clamp mounted on said bar, a rotatable dog for disengaging said yarn clamp, and means for rotating said dog to 100 disengage said clamp.

5. In a tube frame, in combination, a bar having tubes secured thereto, end brackets secured to said bar, a rotatable shaft mounted in said brackets, a fixed shaft mounted 105 in said brackets, a yarn clamp mounted on one of said shafts, a dog mounted on the other of said shafts, said dog being adapted to disengage said clamp upon rotation of said dog, and means for rotating said dog. 110

6. In a tube frame, in combination, a bar having tubes secured thereto, end brackets secured to said bar, a fixed shaft mounted in said brackets, a rotatable shaft mounted in said brackets, a yarn clamp rotatably mounted on said fixed shaft, a dog fixedly secured to said rotatable shaft and adapted to disengage said yarn clamp upon rotation of said shaft, and means for rotating said shaft. 115

7. A tube frame for use with an independent supply of yarn, comprising in combination, a bar having tubes secured thereto, a plurality of yarn clamps along said bar, spring-pressed means for independently operating said clamps in the clamping direction, and means cooperating with a part on the loom for simultaneously releasing all of said clamps. 120

8. In a tube frame adapted to be supplied with yarn from a source mounted independ- 130

ently thereof, a plurality of yarn ends extending through said tubes, clamping means operated independently of said yarn ends mounted on said tube frame for preventing movement of the yarn ends relative thereto, and means for normally holding said clamping means in engagement with the yarn.

9. In a tube frame adapted to be supplied with yarn from a source mounted independently thereof, a plurality of yarn ends extending through said tubes, clamping means independent of said yarn ends mounted on said tube frame for preventing movement of the yarn ends relative thereto, means for normally holding said clamping means in engagement with the yarn, and means for moving said yarn clamping means out of contact with the yarn.

10. In a tube frame, in combination, a bar having tubes secured thereto, said bar having a surface parallel to said tubes and yarn clamping means carried by said frame having a portion for normally engaging the yarn upon said surface but having all other portions disposed clear of the yarn.

11. In a tube frame, in combination, a bar having tubes secured thereto, said bar having a surface parallel to said tubes, yarn clamping means carried by said frame including a member for normally engaging the yarn upon said surface and means carried by said frame for disengaging said yarn clamping means, said member being out of contact with the yarn when in its disengaged position.

12. In a tube frame, in combination, a bar having tubes secured thereto, said bar having a clamping surface above and parallel to said tubes, a yarn clamp rotatably mounted on said bar having a portion for engaging the

yarn upon said surface but having all other portions disposed clear of the yarn, and resilient means including a torsion spring for normally holding said clamp against the yarn to prevent movement of the yarn relative to said surface.

13. In a tube frame, in combination, a bar having tubes secured thereto, said bar having a clamping surface above and parallel to said tubes, a yarn clamp rotatably mounted on said bar for engaging said surface, resilient means for normally holding said clamp against the yarn to prevent movement of the yarn relative to said surface and means associated with and carried by said frame adapted to be positively actuated for disengaging said clamp.

14. In a tube frame, in combination, a bar having tubes secured thereto, said bar having a clamping surface above and parallel to said tubes, a yarn clamp rotatably mounted on said bar for engaging said surface, resilient means for normally holding said clamp against the yarn to prevent movement of the yarn relative to said surface, and means associated with and carried by said frame adapted to be positively actuated by means on the loom frame for disengaging said clamp.

15. In a tube frame, in combination, a bar having tubes secured thereto, a spring pressed yarn clamp rotatably mounted on said frame for resiliently engaging a surface on said frame, an arm mounted on said frame for disengaging said yarn clamp, and means including a member mounted on said frame for operating said arm.

In testimony whereof I hereunto affix my signature.

GEORGE CROSSLAND.
